(57) **CLAIM**

The ornamental design for an epithesis insert, as shown and described.

DESCRIPTION

FIG. 1 is a perspective view of a top and a side of the epithesis insert showing a first embodiment of my new design;

FIG. 2 is a front elevational view thereof;

FIG. 3 is a side elevational view thereof, the other side is a mirror image;

FIG. 4 is a perspective view of the bottom and side thereof;

FIG. 5 is a top plan view thereof;

FIG. 6 is a bottom plan view thereof;

FIG. 7 is a front elevational view of the epithesis insert showing a second embodiment of my new design;

FIG. 8 is a perspective view of the top thereof;

FIG. 9 is a perspective view of the top and side thereof;

FIG. 10 is a top plan view thereof;

FIG. 11 is a side elevational view thereof, the other side is a mirror image; and,

FIG. 12 is a bottom plan view thereof.
